UNITED STATES PATENT OFFICE

149,077

DESIGN FOR A BUILDING

Raymond Loewy, New York, N. Y.

Application August 30, 1946, Serial No. 132,967

Term of patent 14 years

(Cl. D13—1)

To all whom it may concern:

Be it known that I, Raymond Loewy, a citizen of the United States and resident of New York, in the county of New York, and State of New York, have invented a new, original, and ornamental Design for a Building, of which the following is a specification.

This application is a continuation-in-part of my copending application Serial No. D. 120,790, filed July 18, 1945, now abandoned.

In the drawing:

Figure 1 is a perspective view of the building showing my new design.

Figure 2 is a top plan view of the building as shown in Figure 1.

Figure 3 is a rear elevational view of the building as shown in Figures 1 and 2.

Figure 4 is a perspective view of the building taken from the opposite side to that of Figure 1.

I claim:

The ornamental design for a building, as shown.

RAYMOND LOEWY.
